UNITED STATES PATENT OFFICE.

JAMES C. BOTHWELL, OF FAIRFIELD, ILLINOIS.

DOOR-HINGE.

1,082,677.

Specification of Letters Patent. Patented Dec. 30, 1913.

Application filed June 16, 1913. Serial No. 773,959.

To all whom it may concern:

Be it known that I, JAMES C. BOTHWELL, citizen of the United States, residing at Fairfield, in the county of Wayne and State 5 of Illinois, have invented certain new and useful Improvements in Door-Hinges, of which the following is a full, clear, and exact description, reference being had to the accompanying drawings, forming a part 10 hereof.

My invention has relation to improvements in door-hinges; and it consists in the novel details of construction more fully set forth in the specification and pointed out in 15 the claims.

In the drawings, Figure 1 represents a front elevation of a closed door (broken in the middle) showing my invention applied thereto; Fig. 2 is a vertical cross-section on the line 2—2 of Fig. 1; Fig. 3 is an enlarged elevation of the lower inner corner of the door swung partially open; Fig. 4 is a horizontal cross-section on the line 4—4 of Fig. 1; Fig. 5 is a plan of my improved wedge- 25 rail; Fig. 6 is an outside elevation thereof; and Fig. 7 is an elevation of the hinge used in conjunction with the wedge.

The object of my invention is to provide a door-hinge which will permit a door to 30 swing automatically to a closed position when once started toward said position, or to permit the door to automatically complete its swing to full open position after the door has been swung through a given arc toward 35 said position. The results here attained are accomplished through the instrumentality of a hinge which allows of free vertical movements to the door acting in conjunction with a curved wedge or rail which the door 40 traverses in its opening and closing movements.

The advantages of the invention will be 45 fully apparent from a detailed description thereof which is as follows: Referring to the drawings, D represents a conventional door and F the door-frame in which the same is mounted, the floor line being represented by A. In the present embodiment of my invention I employ a hinge having a leaf a secured to 50 the frame F, and a leaf a' secured to the door. The leaf a' is provided with a knuckle b having race-ways c for suitable ball-bearings d whereby the loop b rides freely up and down over the hinge pin e secured be-

tween the terminal loops h, h, of the stationary leaf a.

Secured to the floor A in proximity to the hinge-axis of the door is a reversible wedge-rail 1, the flange of the rail being secured in position by means of angle-brackets 2 60 screwed to the floor; or any other equivalent mechanical manner. The rail or wedge curves in the arc of a circle, the upper face or flange of the rail being traversed by a roller or caster 3 secured to the bottom of the door at such a distance from the hinge-axis as will cause it to sweep along an arc conforming to the curvature of the rail. The rail has a face m, and an extension or complementary face m' meeting at a ridge r, their being a face m, m', on each side of the rail, the opposite faces m, m, meeting in a bevel edge n, the faces m, m', being the shorter; and their free ends being spaced apart as shown (Fig. 6). The several faces 70 are disposed symmetrically about a common central plane indicated by the line x in Fig. 6. On each face m' is a depression or countersink 4 to receive the caster 3.

The operation may be described as follows:—Assuming the door to be closed (Fig. 1) it will be seen that as the door is swung open, the roller 3 (which for a closed and lowest position of the door rests substantially on the bevel n of the rail) will ride up the incline m (Fig. 3) until it passes the ridge r after which it will automatically ride down the incline m' until the roller settles in the depression 4, a buffer 5 being secured to the base-board to arrest the door as well understood in the art. The roller settling in the depression 4 prevents the open door from being dislodged by air currents and the like, although the depression is not of sufficient depth to offer any material amount of resistance to a person closing the door. If it be desired to close the door, the latter is swung so as to cause the roller 3 to ride up the incline m' to and past the ridge r after which the door will automatically close, the roller riding down the incline m partly under gravity and partly under the momentum of the door. In its swinging movements from closed to open, and from open to closed positions, the door moves up and down along its hinge-axis, the vertical play being allowed therefor by the special construction of hinge (Fig. 7) the

knuckle *b* journaled on the pin *e* operating with very little friction by reason of the roller-bearings *d*. The rail *1* having its opposite faces inclined to a common plane (*x*) it follows that it is reversible, that is to say it may be applied to a door hinged on the left or right side. In the drawing the door *D* is hinged on the left; but were it hinged on the right side it would necessitate reversing the rail *1*, that is to say laying it on the face *m* which is shown on top in the drawings. To secure a better support for the rear terminal of the rail after it is once deposited on the floor a wedge or block *6* is placed between the floor and the bottom face *m'* (Fig. 6).

The faces *m*, *m'*, inclining as they do in opposite directions from a common ridge *r*, it follows that for a sweep of the door from 20 a closed to a full open position the door will first ride up the incline *m*, then down the incline *m'*, and vice versa with a closing movement. After the roller passes the ridge *r*, the door will automatically open or close 25 (as the case may be) without a jar under the action of gravity assisted by the slight momentum which it may have acquired with its initial movement. On account of the rising and falling movement of the door, the 30 top of the frame is provided with a cross-strip *7* which covers up the gap which would otherwise result when the door was in its closed and lowest position.

It may be stated in conclusion that while 35 I have stated that the momentum and gravity act jointly to carry the door past the ridge *r* when swung in either direction, that gravity alone will suffice to carry the door where there is no appreciable momentum. 40 It may be further stated that the door in descending the incline *m* automatically latches itself, the door being provided with the usual latch and the frame *F* with a keeper therefor well understood in the art and not 45 shown in the drawings.

Having described my invention, what I claim is:—

1. In combination with a door hinged to swing about a fixed vertical axis and having a rising and falling movement along said axis, a roller at the bottom of the door contiguous to said axis, and a reversible curved rail or track having opposite faces inclined to a common central plane and terminating in an edge at one end, and complementary faces at the opposite ends forming continuations of the first faces but inclining in the opposite direction for the purpose set forth.

2. In combination with a swinging door oscillating about a fixed vertical axis and having an up and down movement along said axis, a reversible curved rail engaging the bottom of said door at a point removed a suitable radial distance from said axis, said rail comprising a member having opposite inclined faces tapering to an edge at one end, complementary faces leading from the opposite ends thereof and inclining therefrom in the opposite direction, and a wedge or block interposed below the bottom complementary face and the floor, and means for securing said rail to the floor.

3. In combination with a door hinged to swing about a fixed vertical axis and having a rising and falling movement along said axis; a reversible curved rail or track engaged by the bottom of the door at a point contiguous to said axis, said rail having opposite faces inclined to a common central plane and terminating in an edge at one end, and complementary faces at the opposite ends forming continuations of the first faces, but inclining in the opposite direction.

In testimony whereof I affix my signature, 85 in presence of two witnesses:

JAMES C. BOTHWELL
